Application March 22, 1933, Serial No. 662,155
 In Germany March 26, 1932

8 Claims. (Cl. 175—363)

This invention relates to improvements in protective systems for electron discharge devices, and more particularly to such systems when associated with devices supplying current to an output circuit of inductive character.

It is well known that, if an electron discharge device provided with control electrodes supplies current to an output circuit of any character, upon occurrence of an overload or of a short circuit in such output circuit, the control electrodes may be utilized to interrupt the resulting flow of current. To obtain such effect, suitable means are provided whereby the control electrodes are brought to and maintained at negative potentials with respect to the potential of a cathode of the device, thereby preventing the transfer of the discharge within the device from one anode to another. The flow of current is then confined to a single anode and is then interrupted by external means if the device receives current from a direct current source, or the flow of current ceases automatically when the voltage impressed on such anode becomes negative if the device is supplied from an alternating current source. It is always essential that the flow of overload or short circuit current be interrupted in the shortest possible time as the flow of such current is of a nature to damage or even destroy the electron discharge device and the associated equipment. If the device is utilized to supply the plate circuit of radio transmitting tubes, momentary breakdown of the impedance of a tube may permit the flow of an excessive current which will cause destruction of the tube unless such current is interrupted within a sufficiently short time. If the output circuit of the device is inductive, the inductance thereof tends to maintain the flow of current therethrough for a considerable length of time even when the source tends to make the anode negative with respect to the cathode of the device, such result being due to the additional electro-motive forces introduced in the circuit by the flow of current through the inductive portions thereof. To obtain a rapid interruption of the flow of current, it is then necessary to neutralize the effect of such inductance by bridging the inductive members with suitable impedance means which prevent the inductance from further acting on the flow of current in the circuit.

It is, therefore, among the objects of the present invention to provide a protective system for electron discharge devices supplying circuits containing inductive members in which system the current flowing through the device is interrupted

within a minimum length of time upon occurrence of an overload or of a short circuit in the output circuit.

Another object of the invention is to provide a protective system for electron discharge devices supplying circuits containing inductive members in which system the current flowing through the device is caused to be interrupted by negatively energizing the control electrodes of the device with respect to the cathode potential.

Another object of the invention is to provide a protective system for electron discharge devices supplying circuits containing inductive members in which system the current in the device is interrupted within a minimum length of time irrespective of the presence of the inductive members in the output circuit.

Another object of the invention is to provide a protective system for electron discharge devices supplying circuits containing inductive members in which such members are shunted by resistance means upon occurrence of an overload or of a short circuit in the output circuit.

Another object of the invention is to provide a protective system for electron discharge devices supplying circuits containing inductive members in which such members are shunted by a condenser upon occurrence of an overload or of a short circuit in the output circuit.

Another object of the invention is to provide a protective system for electron discharge devices supplying circuits containing inductive members in which the current in the device is interrupted when such inductive members receive substantially the entire output voltage of the device.

Objects and advantages, other than those above described, will be apparent from the following description when read in connection with the accompanying drawing, in which:

Fig. 1 diagrammatically illustrates one embodiment of the present invention in which an electron discharge device is operable as an alternating current rectifier supplying current to an output circuit over a reactor, and in which the reactor is bridged by a resistance upon occurrence of an overload or a short circuit in the output circuit.

Fig. 2 diagrammatically illustrates a portion of a modified embodiment of the present invention differing from that illustrated in Fig. 1 in that the reactor may be bridged by a condenser charged from the output line; and

Fig. 3 is a diagram of the output voltage and output current of the device upon occurrence of

an overload or a short circuit in the output circuit.

Referring more particularly to the drawing by characters of reference, reference numeral 6 designates an alternating current supply line of any desired frequency and number of phases, herein shown as a three phase line only for the reason that such type of line is most frequently utilized in practice. Line 6 is connected with the 10 electron discharge device 13 preferably over a transformer having a primary winding 8 and a secondary winding 9 comprising a plurality of phase portions connected in star to form a neutral point 10. The connection between line 6 and winding 8 may be controlled by means of a 15 circuit breaker 7 operable by any suitable known means in response to any conditions of the system. The different phase portions of winding 9, such as 9a, are severally connected with the 20 anodes, such as 11, of the electron discharge device 13 having control electrodes such as 12 associated with the anodes and having a cathode 14. It will be assumed that cathode 14 is connected with the positive conductor 17 of the direct current output circuit over a reactor 16. The negative conductor 18 of the output circuit is connected with neutral point 10 of transformer secondary winding 9. A condenser 19 is connected 25 between conductor 17 and 18 for the purpose of cooperating with reactor 16 to smooth the wave of the output current and voltage. During normal operation of device 13, the control electrodes are preferably maintained at a positive potential with respect to the potential of cathode 14, by 30 means of a battery 21, each control electrode being connected with the battery over a resistance, as at 22, and over the contacts of a relay 23. Relay 23 is operable to reverse the connections of battery 21 upon energization of the 35 coil 24 thereof. Reactor 16 may be bridged by a resistance 26 of suitable value and current carrying capacity over the contacts of a relay 27 having an operating coil 28. Coils 24 and 28 receive current upon breakdown of a spark gap 30 connected in series therewith, the flow of such 40 current being limited by resistance 26 and a suitable additional resistance 29. Coils 24 and 28 are also bridged by a protective resistance 31 for the purpose of diverting any dangerous 45 voltage surges which may be impressed on the coils.

In operation, the system being connected as shown and line 6 being energized, upon closure of circuit breaker 7 winding 8 receives current 50 from line 6 and induces voltages in the several portions of winding 9; the anodes of device 13 are thereby sequentially energized and sequentially carry currents which combine at cathode 14 to form a direct current flowing over reactor 16, conductor 17, the load circuit (not shown) and conductor 18 back to winding 9. The direct current voltage and the direct current present ripples of predetermined frequencies which are reduced to any desired extent by suitable choice 55 of reactor 16 and condenser 19. Upon occurrence of a short circuit in line 17, 18, the condenser 19 discharges through such short circuit and has no further action so that conductor 17 may be considered as directly connected with 60 neutral point 10 of transformer secondary winding 9. The entire output voltage of device 13 is thus impressed across reactor 16 which limits the flow of output current. Such full output voltage is also impressed across spark gap 30 which is 65 adjusted to break down at such voltage, thereby

permitting flow of current over relay coils 24 and 28, resistance 29 and resistance 26. Relays 23 and 27 are so adjusted that relay 23 operates first to reverse the connections of battery 21 with cathode 14 and the control electrodes of device 13 thereby impressing a potential negative relative to cathode potential on the control electrodes. Assuming that, at the instant considered, anode 11 is carrying current, the discharge will not be able to transfer to another anode because of a negative energization of the control electrodes, so that anode 11 continues to carry current alone as is well known. Control electrode 12 is then without action on the flow of such current.

Referring to Fig. 3, curve 32 represents the voltage of cathode 14 with respect to point 10, the curve of such voltage being formed by portions of the phase output voltages of winding 9 minus the arc drop within device 13. Curve 33 represents the direct current which has a wave shape similar to that of curve 32. Assuming that a short circuit in line 17, 18 occurs at a time represented by point A, the output voltage of device 13 which is then impressed across reactor 16 remains substantially as represented by curve 32. The current, however, begins to increase to a considerably higher value. Assuming that relay 23 reverses the connections of battery 21 at a time corresponding to point B, and assuming that anode 11 is carrying current, the output voltage of device 13 is then represented by a sine curve 34 which is substantially the voltage curve of transformer secondary winding portion 9a. The successive half wave portions of curve 34 are alternately positive and negative, but the action of reactor 16 maintains a continuous flow of current through device 13 over a period of time comprising a large number of cycles of the voltage of line 6 by always maintaining cathode 14 negative with respect to anode 11 so that current may continuously flow through device 13. Such current is then represented by curve 36 in Fig. 3 and generally comprises an alternating component to which is added a decreasing direct component due to the slow dissipation of the magnetic energy stored in reactor 16. Relay 27 is so adjusted as to close at a time represented by point C which is approximately the time at which curve 34 passes through zero. The voltage impressed on anode 11 by transformer winding portion 9a is then zero and the current represented by the curve 36 is momentarily at a substantially constant value. Reactor 16 then being bridged by resistance 26, the greater portion of such current is transferred to resistance 26 and the magnetic energy stored in reactor 16, which caused the current flowing therethrough to be unidirectional, is rapidly dissipated in resistance 26 by the flow of a rapidly increasing current. The flow of current thereafter tends to become alternating, and the voltage of winding portion 9a then being substantially zero or even negative, the flow of current through device 13, which flow cannot reverse, is no longer sustained by such voltage and ceases within a very short period of time, at a time such as the time corresponding to point D. Due to the negative energization of the control electrodes of device 13, the flow of current continues to be interrupted until relay 23 returns to the position shown. By selecting point C near the passage of curve 34 through zero, the flow of current is interrupted without production of surges and without unduly burdening the resistance 26 but the value of resistance 26 must be such

that the flow of current ceases before the voltage of transformer winding portion 9a reaches the lowest negative value thereof at point E as the continuation of the flow of current beyond such point would permit such current to increase again due to the rising voltage of winding portion 9a and prevent the interruption of the discharge until the next cycle of the voltage.

Upon occurrence of a backfire within device 13, the magnetic energy stored in reactor 16 will again tend to maintain the flow of current within device 13, such action being again substantially neutralized by the connection of resistance 26 as above described.

In the embodiment illustrated in Fig. 2 resistance 26 is replaced by a condenser 37 connected between cathode 14 and conductor 18 by a high resistance 38. Such resistance permits the slow charge or discharge of condenser 37 but does not provide a path for a rapid discharge thereof, similar to the discharge of condenser 19, upon occurrence of a short circuit in lines 17, 18. When condenser 37 is connected in parallel with resistance 16 over the contacts of relay 27, such condenser and such reactor constitute a resonant circuit in which voltage surges may reach a high value. Such voltage surges may be dissipated over a spark gap 41 and a resistance 39.

The operation of the present embodiment is similar to that of the embodiment illustrated in Fig. 1. Upon occurrence of a short circuit in line 17, 18, spark gap 30 breaks down, thereby causing relays 23 and 27 to operate in the above set forth sequence. Condenser 37 being charged at the normal voltage of line 17, 18 and being connected between the cathode 14 and point 10 of transformer winding 9 over the short circuit, the condenser tends to maintain cathode 14 at the normal voltage thereof with respect to point 10 as represented by curve 32. When the voltage impressed on anode 11 from winding portion 9a decreases below the normal value, the flow of current between anode 11 and cathode 14 ceases and is not reestablished because of the negative energization of the control electrodes of all anodes as above described. Such current interruption is slightly delayed because, while the voltage of anode 18 is decreasing, condenser 37 is discharging over reactor 16 to neutralize the magnetic energy stored in the reactor. By a suitable choice of the condenser 37 the discharge of such condenser leaves the voltage thereof at a value sufficient to permit interruption of the current in device 13 before the time represented by point D.

Although but a few embodiments of the present invention have been illustrated and described, it will be apparent to those skilled in the art that various changes and modifications may be made therein without departing from the spirit of the invention or from the scope of the appended claims.

It is claimed and desired to secure by Letters Patent:

1. In combination, a supply line, an electron discharge device connected with said line, an output line connected with said device, inductive means in said output line, impedance means connected with said output line, means for causing interruption of the flow of current through said device, means for bridging said inductive means with said impedance means, and means responsive to abnormal conditions in said output line to cause sequential operation of the third and fourth said means.

2. In combination, a supply line, a transformer

connected with said line, an electron discharge device connected with said transformer, an output line connected with said transformer and with said device, inductive means in said output line, impedance means connected with said output line, means for neutralizing the conductivity of said device to interrupt the flow of current therethrough, means for bridging said inductive means with said impedance means, and means responsive to abnormal conditions in said output line to cause sequential operation of the third and fourth said means.

3. In combination, a supply line, a transformer connected with said line, an electron discharge device connected with said transformer, an output line connected with said transformer and with said device, inductive means in said output line, impedance means connected with said output line, means for causing interruption of the flow of current through said device, means for bridging said inductive means with said impedance means, and means responsive to the magnitude of the flow of current in said output line to cause sequential operation of the third and fourth said means.

4. In combination, a supply line, a transformer connected with said line, an electron discharge device connected with said transformer, an output line connected with said transformer and with said device, inductive means in said output line, impedance means connected with said output line, means for causing interruption of the flow of current through said device, means for bridging said inductive means with said impedance means, and means responsive to the magnitude of the voltage across said inductive means to cause operation of the third and fourth said means.

5. In combination, a supply line, a transformer connected with said line, an electron discharge device connected with said transformer and having anodes with associated control electrodes and a cathode, an output line connected with said transformer and with said device, means for rendering said control electrodes negative with respect to said cathode, inductive means in said output line, impedance means connected with said output line, means for bridging said inductive means with said impedance means, and means responsive to abnormal conditions in said output line to cause sequential operation of the third and fourth said means.

6. In combination, a supply line, a transformer connected with said line, an electron discharge device connected with said transformer and having anodes with associated control electrodes and a cathode, an output line connected with said transformer and with said device, means for rendering said control electrodes negative with respect to said cathode, inductive means in said output line, resistance means connected with said output line, means for bridging said inductive means with said impedance means, and means responsive to abnormal conditions in said output line to cause sequential operation of the third and fourth said means.

7. In combination, a supply line, a transformer connected with said line, an electron discharge device connected with said transformer and having anodes with associated control electrodes and a cathode, an output line connected with said transformer and with said device, means for rendering said control electrodes negative with respect to said cathode, inductive means in said output line, condenser means connected with said

output line, means for bridging said inductive means with said condenser means, and means responsive to abnormal conditions in said output line to cause operation of the third and fourth said means.

8. In combination, an alternating current supply line, a transformer connected with said line, an electron discharge device connected with said transformer and having anodes with associated control electrodes and a cathode, a direct current output line connected with said transformer

and with said device, means for rendering said control electrodes negative with respect to said cathode, inductive means in said output line, impedance means connected with said output line, means for bridging said inductive means with said impedance means, and means responsive to abnormal conditions in said output line to cause sequential operation of the third and fourth said means.

STEFAN WIDMER. 10
